Primary Examiner — Michael C Stout*Assistant Examiner* — Tia Ruth-Renee Polidori*(74) Attorney, Agent, or Firm* — Boris Leschinsky**CLAIM**

The ornamental design for a shaker bottle, as shown and described.

DESCRIPTION

FIG. 1 is a first perspective view of my new design for a shaker bottle;

FIG. 2 is a second perspective view thereof, shown in alternate configuration;

FIG. 3 is a first side view of the shaker bottle of FIG. 1;

FIG. 4 is a second side view, thereof;

FIG. 5 is a rear view thereof;

FIG. 6 is a front view thereof;

FIG. 7 is a top view thereof; and,

FIG. 8 is a bottom view thereof.

The portions of the beverage container and lid with a flip cap shown in broken lines form no part of the claimed design.
